HAIR DRIER HELMET

Bernard Kritzer, Chicago, Ill.

Application February 28, 1947, Serial No. 731,651

3 Claims. (Cl. 34—90)

1

This invention relates to an improved hair dryer helmet for use in beauty parlors and the like. It is more particularly concerned with a helmet adapted to be worn by the customer while seated under a hot air dryer and to extend between the hood of the dryer and the customer's head.

I am aware that helmets of various types intended to confine the hair during drying thereof, and to prevent the hot air from reaching the face of the customer, have been employed. However, those devices have contained inherent defects rendering them unsuited to the intended purpose. For example, some have been of metal and therefore cumbersome and tiring to the wearer. Others have been so constructed as to be an inherent part of the hair drying apparatus and therefore unsanitary. Still others have been made of fabric through the interstices of the weave of which the hot air is able to pass so as largely to defeat the intended function, while others have been made in such manner as to obstruct inspection of the hair during drying to determine the status thereof.

Having in view the foregoing, the principal object of my invention is the provision of a helmet adapted to extend from the rim of the hood of a conventional hair dryer to and around the head of the wearer below the hair line, thus to encompass and enclose the air during drying and to confine the heated air to the hair zone and thereby materially reduce the time required for the process and add greatly to the customer's comfort.

Another object is to provide a helmet as aforesaid in which that part thereof encircling the hood is provided with retractile means to permit rapid engagement and disengagement of the device from the hood.

A further object is to provide a helmet as aforesaid in which that portion adapted to embrace the head of the wearer is provided with securing means easily regulatable as to tension whereby one size of device is capable of use on heads of varying perimeter at the hair line.

Still another object is the provision of a helmet for purpose aforesaid having an opening for inspection of the hair during drying, which opening may be closed by simple, troublefree means.

In the drawing which shows one form in which the invention may be embodied in practice:

Fig. 1 is a view in perspective showing the device in position during use;

Fig. 2 is a view of the developed blank from which the device may be formed;

2

Fig. 3 is a cross-sectional detail taken on the line 3—3 of Fig. 1;

Fig. 4 is a detail in perspective showing a modified form of inspection opening and flap; and

Fig. 5 is a cross-sectional detail taken on the line 5—5 of Fig. 4.

Referring now to the drawing, the hood 10 of the hair drying apparatus (shown somewhat diagrammatically) has a rim portion 11 about which the upper hem of my device is adapted to be secured. It will be understood that heated air issues from the hood 10 and is directed downwardly about the hair of the customer to accelerate the drying thereof.

15 The helmet preferably comprises a principal body portion 13 formed by cutting a blank 13a to the contour shown in Fig. 2, i. e., wider in the center and narrower at the ends in order to comprise, when the outer edges are brought together, an article substantially wider at the front

20 than at the rear, and for a purpose to be described. The material employed may be nylon woven with a rather coarse mesh and impregnated with a flexible plastic material not subject to embrittlement

25 under continued heat, or any other material having the characteristics of flexibility and heat immunity. At its upper border the blank is folded over and hem-stitched as at 14 (Fig. 3) to form an elongated edgewise pocket through which a length of elastic, e. g., elastic tape, may be threaded and the ends thereof joined to yield an endless band 15. By such means the device may easily be manually expanded and placed over the hood 10, whereupon the contractile force of the elastic

30 maintains the device in snug engagement.

25 At its lower edge, the blank 13a is folded and hemstitched to form a pocket 14a similar to that already described, and through which lower pocket a fabric tape or cord is threaded to form

30 a drawstring 16. The V-shaped notch 17 provided at the centre of the blank is utilized for an inspection opening 18, the material being hemmed or otherwise reinforced at 19 to afford a border for the opening not easily torn while the article is in use.

35 If desired, the device may be formed of a flexible plastic material not having the fabric base, and the pockets at the upper and lower edges and the reinforcing hem of the opening 18 united by so-called "electronic sewing" in which process the plastic is raised to fusing temperature by a high frequency electrical current.

40 As shown in Fig. 1, the article is so contoured and is of such dimensions that the fabric is 50 gathered by the band 15 and drawstring 16 into a

ruffled or pleated formation, leaving the fabric therebetween rather full. By such expedient and selection of a fabric of soft handle, the device readily conforms itself to the coiffure, thus serving its intended function while being incapable of disturbing the set or wave of the hair. Moreover, it will be noted that by imparting a shorter vertical dimension to the rearward part of the device and a substantially longer corresponding dimension to the forward portion the upper hem may be secured properly about the hood 10 while the lower hem will lie just below the hair line, the latter following a somewhat sloping contour compared to the crown of the head. Additionally such conformation of the device enables the drawstring 16 to be taken up about the forehead and nape of the neck to insure against inadvertent dislodgment.

The invention is further characterized in an alternative embodiment by being provided with an inspection opening having a covering flap. Turning to Figs. 4 and 5, the opening 18a is provided with foldable flap 21 thereover joined by one edge 22 to the body 13 of the device. The opposite edge of the flap may be fastened by any convenient means, for example, a pair of snap fasteners 23 of common form. By using either opening 18 or 18a the operator may insert a hand inside the helmet to determine the stage at which the customer's hair is at the moment, and may do so without disturbing the position of the device.

An important feature of the invention resides in the cutting of the original blank in a manner to produce substantial fullness in the device when applied to the dryer hood and the head of the wearer. Such result is attained by providing a dimension to the upper and lower edges of the blank somewhat greater than the perimeter of the hood and the customer's head respectively, so that when the subsequently hemmed edges are gathered, as by fastening the device in position, the material intermediate the secured edges may be full enough to enclose the mass of hair without subjecting the same to pressure such as may crush or otherwise impair the set thereof.

Attachment of the device to the dryer hood and customer's head is not intended to be limited to that shown and described since equivalent means may be employed. For example, the lower edge of the helmet may comprise an elastic tape secured directly to the body 13 or enclosed in a pocket; or the upper edge may be provided with a drawstring in lieu of an elastic tape. Moreover, the inspecting opening may be in multiple, e.g., one in front and one in back.

As an additional feature, openings 25 in the nature of perforations may be provided about the perimeter of the device to vent the hot air delivered to the hair.

While I have shown particular embodiments of my invention, it will be understood, of course, that I do not wish to be limited thereto since many modifications may be made, and I therefore contemplate by the appended claims to cover any such modifications as fall within the true spirit and scope of my invention.

Having thus described my invention, what I claim and desire to secure by Letters Patent is:

- 10 1. A helmet of the type described comprising a band adapted to encompass the hair of the wearer and including means at the upper and lower peripheries of the band for securing the helmet to the dryer hood and the customer's head respectively, said band having a hair-inspecting opening therethrough, and a closure for said opening hingedly secured along at least one edge thereof to said band.
- 20 2. A helmet of the type described comprising a band adapted to encompass the hair of the wearer and including means at the upper and lower peripheries of the band for securing the helmet to the dryer hood and the customer's head respectively, said band having a hair-inspecting opening therethrough, and a closure for said opening hingedly secured along at least one edge thereof to said band, and means common to said band and closure for securing the free portions thereof to said band.
- 30 3. A helmet of the type described comprising a band adapted to encompass the hair of the wearer and including means at the upper and lower peripheries of the band for securing the helmet to the dryer hood and the customer's head respectively, said band having a hair-inspecting opening therethrough, and a closure for said opening hingedly secured along at least one edge thereof to said band, and means common to said band and closure for securing the free portions thereof to said band, said closure being arranged in overlapping relation with the boundary of said opening.

BERNARD KRITZER.
